RAILWAY SIGNALING.

Application filed May 13, 1922, Serial No. 560,568. Renewed December 2, 1926.

My invention relates to railway signaling, and particularly to signaling of the type wherein the signals are controlled by track circuits or other circuits containing sources 5 of current which are reversible as to polarity.

One object of my invention is the provision of novel and improved means for preventing a signal from momentarily giving a stop indication when the polarity of the 10 current supplied to the associated controlling circuit is reversed.

I will describe several forms of railway signaling systems embodying my invention and will then point out the novel features 15 thereof in claims.

In the accompanying drawings, Fig. 1 is a diagrammatic view showing one form of signaling system embodying my invention, the system in the form here shown comprising 20 light signals. Fig. 2 is a view similar to Fig. 1 and also embodying my invention, but showing a system comprising semaphore signals. Fig. 3 is a view showing a modification of the light signal system shown in Fig. 25 1, and Fig. 4 is a view showing a modification of the semaphore signal system shown in Fig. 2, both also embodying my invention.

Similar reference characters refer to similar parts in each of the several views.

Referring first to Fig. 1, the reference characters 3 and 3^a designate the track rails of a railway along which traffic normally moves in the direction indicated by the arrow. These rails are divided by insulated joints 2 to form a track section A—B, which section is provided with a track circuit comprising as usual a source of current and a track relay. The source of current is the secondary 51 of a transformer T^b, the primary 51^a of which is connected with a transmission line F to which alternating signaling current is constantly supplied by a generator H. Secondary 51 is connected with the rails of section A—B through the medium of a pole-changing device which is hereinafter explained. The relay for section A—B is designated by the reference character D^a, and as here shown is of the polyphase motor type, comprising a rotor 4, a stator 50 winding 5 connected with the track rails, and a second stator winding 6 constantly supplied with signaling current from a secondary 11 on a transformer T^a. The pri-

mary 32 of the latter transformer is connected with the transmission line F. 55

The track section B—C lying to the right of section A—B is also provided with a track circuit comprising the secondary 51 of a transformer T^c, and a relay D^b which is similar to track relay D^a. The contacts 49 and 50 of the relay D^b constitute a pole-changer for reversely connecting secondary 51 of transformer T^b with the rails of section A—B. When relay D^b is energized in either direction, the right-hand terminal of secondary 51 is connected with the lower rail 3^a and the left-hand terminal is connected with the upper rail 3. The current which is then supplied to the rails of section A—B is of what I will term "normal" relative polarity. 70 When relay D^b is de-energized, however, the right-hand terminal of secondary 51 is connected with the upper rail 3 and the left-hand terminal is connected with the lower rail 3^a, so that current of what I will term 75 "reverse" relative polarity is then supplied to the section A—B.

Relay D^a is responsive to reversals of relative polarity of the current supplied to the track rails of its associated section. When 80 the current is of normal relative polarity, contact finger 7 is swung to the right, whereas when the current is of reverse relative polarity this contact finger is swung to the left. When the track section A—B is occupied, 85 relay D^a is, of course, de-energized, so that contact 8 is closed and contact finger 7 occupies a vertical or intermediate position.

Located adjacent the entrance end of section A—B is a signal S^a, which, as here 90 shown, is of the light signal type, comprising three lamps G, Y and R, indicating when illuminated, "proceed", "caution" and "stop", respectively. The proceed lamp G is provided with a circuit which passes from the left-hand terminal of secondary 10 of transformer T^a, through wires 12 and 13, right-hand point of contact 7, wire 14, lamp G, wires 15 and 16 to secondary 10. This lamp is illuminated, therefore, only when 95 relay D^a is energized in normal direction. The caution lamp Y is provided with a circuit which passes from the left-hand terminal of secondary 10, through wires 12 and 13, left-hand point of contact 7, wire 17, lamp 100 Y and wires 15 and 16 to secondary 10. It

follows that this lamp is illuminated only when relay D^A is energized in reverse direction. The stop lamp R is controlled by a thermo-sensitive cell E comprising a heating element 19 and a thermo-sensitive element 21. The heating element 19 is provided with a circuit which passes from secondary 10, through wires 12 and 18, contact 8, heating element 19, and wires 20 and 16 to secondary 10. This circuit is, of course, closed only when contact 8 is closed, that is, when relay D^A is de-energized. The circuit for the stop lamp R is from secondary 10, through wires 12 and 18, contact 8, heating element and thermo-sensitive element of cell E, wire 52, lamp R and wires 15 and 16 to secondary 10. The thermo-sensitive cell E has a negative temperature coefficient; that is, the resistance of the element 21 decreases with increase of temperature. The parts are so adjusted that lamp R is supplied with sufficient current to light this lamp only when cell E is hot; that is, only when current has been supplied for a certain length of time to heating element 19. When the cell is cold and contact 8 is closed a certain period of time will, of course, elapse before the thermo-sensitive element 21 is heated to such temperature as to permit sufficient current to pass therethrough to light the lamp R. This time element is utilized in a manner which will appear hereinafter.

The operation of the apparatus shown in Fig. 1 is as follows:

When both sections A—B and B—C are unoccupied, as shown in the drawing, relay D^B is, of course, energized, so that current of normal relative polarity is supplied to the rails of section A—B. Relay D^A is, therefore, energized in normal direction, so that lamp G is lighted and the signal S^A consequently indicates "proceed". When a car or train moving toward the right enters section A—B, its wheels and axles will shunt the track circuit current from winding 5 of relay D^A , so that this relay will become de-energized. The opening of contact 7 will extinguish the proceed lamp G and the closing of contact 8 will cause the stop lamp R to become lighted. As the train passes from section A—B into section B—C, it will de-energize relay D^B , so that current of reverse polarity will be supplied to the rails of section A—B. Relay D^A will, therefore, become energized in reverse direction, so that the stop lamp R will become extinguished and the caution lamp Y will become lighted. As the train passes out of section B—C, relay D^B will become energized, so that the polarity of the current supplied to section A—B will be reversed. During this reversal contact 8 of relay D^A will momentarily close, thereby completing the circuit for the heating element 19 of the thermo-sensitive cell E. The length of time

during which contact 8 is closed, however, is very short, and is not sufficient to permit the temperature of element 21 to be raised to such point that enough current is supplied to lamp R to light this lamp. The result is that lamp R remains extinguished during the reversal of relay D^A . This reversal closes the circuit for the proceed lamp G so that the parts of the apparatus are then restored to the conditions in which they are shown in the drawing.

Referring now to Fig. 2, the apparatus shown herein is similar to that illustrated in Fig. 1, except that a semaphore signal S^A_1 is substituted for the light signal S^A of Fig. 1. Section B—C is provided with a similar signal S^B_1 , which in turn operates a pole-changer P for controlling the relative polarity of the current supplied to the rails of section A—B by transformer T^B .

The signal S^A_1 is provided with a caution indication circuit and with a proceed indication circuit. The caution circuit is controlled by a thermo-sensitive cell E', comprising a heating element 19, a thermo-sensitive element 29, and an electrode 30. The heating element 19 is provided with a circuit which passes from the left-hand terminal of secondary 10, through wires 21, 22 and 26, contact 8 of relay D^A , wire 27 or 28, heating element 19, and wire 16 to secondary 10. This circuit is closed only when relay D^A is energized in either direction, but open when the relay is de-energized. The caution indication circuit for signal S^A_1 passes from secondary 10, through wires 21 and 54, thermo-sensitive element 29 and electrode 30 of cell E', wire 31, operating mechanism of signal S^A_1 , and wires 25 and 16 to secondary 10. The parts of this circuit are so proportioned that sufficient current is supplied to the signal mechanism to actuate this signal only when the thermo-sensitive cell E' is heated. The proceed indication circuit is from the secondary 10, through wires 21, 22 and 23, contact 7, wire 24, operating mechanism of signal S^A_1 , and wires 25 and 16 to secondary 10. This circuit is, of course, closed only when relay D^A is energized in normal direction.

The operation of the apparatus shown in Fig. 2, is as follows:

When both track sections A—B and B—C are unoccupied, as shown in the drawing, relay D^A is energized in normal direction, so that signal S^A_1 indicates proceed. When a car or train moving toward the right enters section A—B, it de-energizes relay D^A , so that the proceed indication circuit for signal S^A_1 is opened at contact 7 of this relay. At the same time the circuit for the heating element 19 is opened at contact 8, and after a short interval of time, sufficient to permit the cell E' to cool down, the conductivity of this cell is reduced to such value that, in ef-

fect, the caution indication circuit for the signal S^A_1 is open. This signal consequently moves to the stop position. As the train leaves section A—B and passes into section 5 B—C, it places signal S^B_1 in the stop position, and this signal in turn reverses pole-changer P so that current of reverse polarity is supplied to the rails of section A—B. Contacts 7 and 8 of relay D^A are then swung 10 to the left, so that the heating element 19 of the thermo-sensitive cell E' becomes energized. After a short interval of time the temperature of this cell is raised to such value that the caution indication circuit for 15 signal S^A_1 becomes energized, whereupon this signal moves to the caution position. When the train leaves section B—C, signal S^B_1 moves to the caution position and in doing so it restores the pole-changer P to 20 its original position so that current of normal relative polarity is again supplied to the rails of section A—B. This reversal of polarity causes the contacts of relay D^A to swing to the right, during which movement 25 contact 8 is momentarily opened. The interval of time during which this contact is open, however, is so short that the temperature of the cell E' is not materially reduced and so the supply of current to the caution 30 indication circuit for signal S^A_1 is not interrupted. It follows that the signal is not released from the caution position. Contact 7 is now closed, so that signal S^A_1 moves to the proceed position.

35 It will be observed from the foregoing that by virtue of the cell E' the signal S^A_1 is prevented from momentarily moving to the stop position during the reversal of relative polarity of the current supplied to the rails of section A—B.

Referring now to Fig. 3, the apparatus shown therein is the same as that shown in Fig. 1, except as to the means for controlling the supply of current to the stop lamp R of signal S^A . In Fig. 3 the circuit for lamp R includes an electron tube J, comprising a filament 36 and a plate 41. The filament 36 is provided with an energizing circuit which passes from secondary 33 of transformer 45 T^A , through wire 34, contact 9 of relay D^A , wires 35 and 42, filament 36 and wire 37 to secondary 33. Contact 9 is closed only when relay D^A is de-energized. The circuit for the stop lamp R is from secondary 38 to 50 transformer T^A , through wire 39, contact 8 of relay D^A , wire 40, plate and filament of tube J, wires 42 and 43, lamp R and wire 44 to secondary 38. The electrical conductivity of the tube J is relatively low when the filament 36 is de-energized, and relatively high when the filament is heated by energization, and so it will be seen that current of sufficient value to light the lamp R is furnished to this lamp only when filament 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

ment 36 becomes energized, a certain interval of time will elapse before its temperature will be raised to high conductivity value so that the lighting of the lamp R will be delayed for a short interval of time after contact 9 is closed.

In the operation of the apparatus shown in Fig. 3 it will, of course, be observed that when section B—C is occupied signal S^A indicates caution. When the car or train 75 passes out of section B—C the reversal of relative polarity of the current supplied to section A—B will cause contacts 8 and 9 of relay D^A to close momentarily. The momentary energization of filament 36 is not sufficient, however, to raise its temperature to the high conductivity value and so the stop lamp R is not lighted during this momentary closing of contacts 8 and 9.

Referring now to Fig. 4, thermo-sensitive cell E' is similar to the corresponding cell in Fig. 2, but the heating element 19 of this cell is connected directly across the track rails 3 and 3^a of section A—B. The caution indication circuit for signal S^A_1 is 90 from secondary 10, through wires 45 and 53, thermo-sensitive cell E', operating mechanism of signal S^A_1 and wire 48 to secondary 10. This circuit carries sufficient current to operate the signal when heating element 19 95 is energized, but not when the heating element is de-energized. The proceed indication circuit for this signal is from secondary 10, through wires 45 and 46, normal contact 7 of relay D^A , wire 47, operating mechanism of signal S^A_1 and wire 48 to secondary 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

The operation of the apparatus shown in Fig. 4 is as follows:

When sections A—B and B—C are both 105 unoccupied, signal S^A_1 indicates proceed, because the thermo-sensitive cell E' is heated by the track circuit current and the proceed indication circuit is closed at contact 7. When a car or train moving toward the 110 right enters section A—B, relay D^A becomes de-energized and the supply of current to the heating element 19 of the cell E' is also discontinued. The resistance of cell E' is therefore increased, so that the caution indication circuit is in effect open at this point, and the proceed indication circuit for secondary S^A_1 is opened at contact 7, so that this signal moves to the stop position. When the train enters section B—C, current 115 of reverse relative polarity is supplied to section A—B, so that relay D^A becomes energized in the reverse direction wherein contact 7 is open. Current is now supplied, however, to the heating element 19 of the 120 cell E' from the track circuit for section A—B, so that the caution indication circuit for signal S^A_1 becomes conductive and so this signal moves to the caution position. As the train passes out of section B—C, 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

2
pole changer P reverses, thereby supplying current of normal relative polarity to section A—B, whereupon relay D^A becomes energized in normal direction. The closing of contact 7 closes the proceed indication circuit for signal S^A₁ so that this signal moves to the proceed position. During the reversal of polarity of the track circuit current, the treating element 19 is momentarily de-energized, but not for a period of time sufficient to permit cell E' to cool, and so the conductivity of the caution indication circuit is not materially reduced. It follows therefore that signal S^A₁ is not released from the caution position during the reversal of relative polarity of the track circuit current supplied to section A—B.

Although I have herein shown and described only four forms of signaling systems embodying my invention, it is understood that various changes and modifications may be made therein within the scope of the appended claims without departing from the spirit and scope of my invention.

25 Having thus described my invention, what I claim is:

1. In combination, a relay capable of energization in opposite directions, a normal contact closed when the relay is energized in one direction, a reverse contact closed when the relay is energized in the other direction, a third contact closed when the relay is de-energized and also closed momentarily when the direction of energization of the relay is reversed, signaling means controlled by said normal and reverse contacts, a thermo-sensitive cell having a heating element and a thermo-sensitive element, a circuit for said heating element controlled by said third relay contact, and signaling means controlled by the thermo-sensitive element of said cell.

2. In combination, a relay capable of energization in opposite directions, a normal contact closed when the relay is energized in one direction, a reverse contact closed when the relay is energized in the other direction, a third contact closed when the relay is de-energized and also closed momentarily when the direction of energization of the relay is reversed, a thermo-sensitive cell having a heating element and a thermo-sensitive element, a circuit for said heating element controlled by said third relay contact, and signaling means controlled by said normal and reverse relay contacts and by said thermo-sensitive element.

3. In combination, a relay capable of energization in opposite directions, a normal contact closed when the relay is energized in one direction, a reverse contact closed when the relay is energized in the other direction, a third contact closed when the relay is de-energized and also closed momentarily when the direction of energization of the relay is reversed, a thermo-sensitive cell having a heating element and a thermo-sensitive element, a circuit for said heating element controlled by said third relay contact, and signaling means controlled by said normal and reverse relay contacts and by said thermo-sensitive element.

the relay is reversed, a thermo-sensitive cell controlled by said third relay contact, and signaling means controlled by said normal and reverse relay contacts and by said thermo-sensitive cell.

4. In combination, a relay capable of energization in opposite directions, a normal contact closed when the relay is energized in one direction, a reverse contact closed when the relay is energized in the other direction, a third contact closed when the relay is de-energized and also closed momentarily when the direction of energization of the relay is reversed, a thermo-sensitive cell controlled by said third relay contact; and a light signal having a proceed lamp controlled by said normal contact, a caution lamp controlled by said reverse contact and a stop lamp controlled by said thermo-sensitive cell.

5. In combination, a relay capable of energization in opposite directions and having a contact which is closed when the relay is de-energized and also closed momentarily when the direction of energization of the relay is reversed, a thermo-sensitive cell having a heating element and a thermo-sensitive element, means for controlling said heating element by said relay contact, and signaling means controlled by the thermo-sensitive element of said cell.

6. In combination, a relay capable of energization in opposite directions and having a contact which is closed when the relay is de-energized and also closed momentarily when the direction of energization of the relay is reversed, a thermo-sensitive cell controlled by said relay contact, and signaling means controlled by said cell.

7. In combination, a relay capable of energization in opposite directions and having a contact which is closed when the relay is de-energized and is also closed momentarily when the direction of energization of the relay is reversed, a substance having the characteristic of decreasing in electrical resistance with increase of temperature, a circuit including said substance and a signaling device, and means controlled by said relay contact for heating said substance.

8. In combination, a relay capable of energization in opposite directions and having a contact which is closed when the relay is de-energized and is also closed momentarily when the direction of energization of the relay is reversed, a heating element, means controlled by said relay contact for energizing said heating element, and signaling means controlled by said heating element.

9. In combination, a relay capable of energization in opposite directions and having a contact which is closed when the relay is de-energized and is also closed momentarily when the direction of energization of the relay is reversed, a heating element, means controlled by said heating element,

controlled by said relay contact for energizing said heating element, a circuit controlled by said heating element and substantially conductive or substantially non-conductive according as said element is energized or de-energized, and signaling means controlled by said circuit.

10. In combination, a relay capable of energization in opposite directions, a signal controlled by said relay to indicate proceed, caution or stop according as the relay is energized in normal or reverse direction or is de-energized, and means including a thermo-sensitive cell for preventing said signal from momentarily indicating stop when the direction of energization of said relay is reversed.

11. In combination, a relay capable of energization in opposite directions, a signal controlled by said delay to indicate proceed, caution or stop according as the relay is energized in normal or reverse direction or is de-energized, and means including a heating element controlled by said relay for preventing said signal from momentarily indicating stop when the direction of energization of said relay is reversed.

12. In combination, a track circuit comprising track rails and a source of current reversibly connected therewith; a signal controlled by said track circuit and arranged to indicate proceed when the track circuit is energized in one direction, caution when the track circuit is energized in the other direction, and stop when the track circuit is occupied; and means including a thermo-sensitive relay controlled by said track circuit for preventing said signal from momentarily indicating stop when the polarity of the current supplied to the track circuit is reversed.

13. In combination, a track circuit comprising track rails and a source of current reversibly connected therewith; a signal controlled by said track circuit and arranged to indicate proceed when the track circuit is energized in one direction, caution when the track circuit is energized in the other direction, and stop when the track circuit is occupied; and means including a heating element controlled by said track circuit for preventing said signal from momentarily indicating stop when the polarity of the current supplied to the track circuit is reversed.

14. In combination, a relay capable of energization in opposite directions, and having a contact which is closed when the relay is de-energized and is also closed momentarily when the direction of energization of the relay is reversed, a signal comprising a lamp controlled by said contact, and means included in the circuit of said

lamp for delaying the lighting of the lamp to full brilliancy, whereby said lamp does not flash during reversal of said relay.

15. In combination, a relay capable of energization in opposite directions, a normal contact closed when the relay is energized in one direction, a reverse contact closed when the relay is energized in the other direction, a third contact closed when the relay is de-energized and also closed momentarily when the direction of energization of the relay is reversed, a light signal comprising proceed, caution and stop lamps controlled respectively by the normal reverse and third contacts of said relay, and means included in circuit with said stop lamp for delaying the lighting of the lamp to full brilliancy, whereby said lamp does not flash during reversal of said relay.

16. In combination, a relay capable of energization in opposite directions, and having a contact which is closed when the relay is de-energized and is also closed momentarily when the direction of energization of the relay is reversed, a signal comprising a lamp controlled by said contact, and an element having resistance included in the circuit of said lamp for delaying the lighting of the lamp to full brilliancy, whereby said lamp does not flash during reversal of said relay.

17. In combination, a relay capable of energization in opposite directions, a normal contact closed when the relay is energized in one direction, a reverse contact closed when the relay is energized in the other direction, a third contact closed when the relay is de-energized and also closed momentarily when the direction of energization of the relay is reversed, a light signal comprising proceed, caution and stop lamps controlled respectively by the normal, reverse and third contacts of said relay, and an impedance included in circuit with said stop lamp for delaying the lighting of the lamp to full brilliancy, whereby the said lamp does not flash during reversal of said relay.

18. An electric circuit comprising an electric lamp, and means associated with said circuit and operating when the circuit is closed momentarily to prevent the flow of sufficient current to said lamp to light the lamp.

19. A railway signal comprising an electric lamp, a circuit for said lamp including a source of energy, and means associated with said circuit and operating when the circuit is closed momentarily to prevent the flow of sufficient current to said lamp to light the lamp.

In testimony whereof I affix my signature.

FRANK H. NICHOLSON.
